UNITED STATES PATENT OFFICE

113,689

DESIGN FOR A MEDIUM RANGE LOAD CARRYING AIRPLANE

James G. Taylor and Harold W. Case, Dayton, Ohio, assignors to the Government of the United States of America, as represented by the Secretary of War

Application August 14, 1935, Serial No. 58,126

Term of patent 7 years

To all whom it may concern:

Be it known that we, James G. Taylor and Harold W. Case, citizens of the United States residing at Dayton, in the county of Montgomery and State of Ohio, have invented a new, original, and ornamental Design for Medium Range Load-Carrying Airplane, of which the following is a specification, reference being had to the accompanying drawing, forming part thereof, wherein:

Fig. 1 is a top plan view of an airplane showing our new design;

Fig. 2 is a front elevational view of the said airplane design;

Fig. 3 is a side elevational view of said airplane design; and

Fig. 4 is a top perspective of said airplane design.

The dominant feature of our design resides in the fuselage and lateral supporting surfaces.

We claim:

The ornamental design for a medium range load carrying airplane, as shown and described.

JAMES G. TAYLOR.
HAROLD W. CASE.
